UNITED STATES PATENT OFFICE.

CARL MARCH, OF CHICAGO, ILLINOIS.

CONFECTIONER'S PATTERN-MAKING DEVICE.

Application filed March 23, 1927. Serial No. 177,697.

The object of this invention is to provide an article for use by confectioners in producing a variety of designs to be followed in applying icing to a cake or the like, the device permitting of assembly in a particularly convenient manner, for sale, and comprising a plurality of elements each affording means for producing a distinctive design, or unit of a more elaborate design.

10 A further object is to provide an article of this kind which shall include, as one of the principal parts thereof, a spider-like frame adapted to receive a plurality of segmental members, each of which carries marking devices, these devices being intended for assembly in accordance with the plans of the user, for producing particular designs and variations thereof.

With the foregoing and other objects in view, the invention consists in the novel construction and arrangement of elements described, illustrated and claimed, it being understood that modifications may be made within the scope of the claims without departing from the spirit of the invention.

In the drawings forming part of this application,

Figure 1 is a view in vertical transverse section.

30 Figure 2 is a fragmentary view in vertical section of a part of the device.

Figure 3 is a top plan view of one of the elements of the construction, and of the segmental members.

35 Figure 4 shows the spider-like element, and a plurality of segmental devices, inserted therein, and adapted to carry marking elements, for the purpose of tracing a design, or producing a design to be worked out when applying icing to the cake or other article, this view being in bottom plan.

40 Figure 5 is a perspective view of one of the segmental elements.

Figure 6 is a diagrammatic view showing 45 one form of design which may be employed, say for the top of the article.

Figure 7 is a fragmentary view in vertical section showing the upper element of the construction of Figure 1, and a portion 50 of the container.

Figure 8 shows a complete design formed by building up the unitary elements, such as those shown in Figures 4 and 5 or produced as a fixed design, formed by the pins of the 55 lower element.

A box-like container is designated 10, and

is shown as being of annular form, and as including or having connected therewith, in accordance with the desire of the manufacturer, an inner annular flange or ring 11, 60 this element being provided with an annular shoulder 12 adapted to support one of the units, and the complete element 11 supporting at their outer portions, all of the units, of the type shown in Figure 5. 65 Formed as a part of the same construction, or connected therewith are radial elements 13 extending from a central hub-like member 14, these devices 13 dividing the structure in such manner that the segmental elements may be inserted in any position, or in any relation desired, in order to produce a particular design of complete form. It will be observed that a shoulder or annular portion 16 is also provided at the central part 70 of the spider, for supporting the segmental devices at the inner ends thereof.

75 These segmental devices or units of Figure 5 each comprise a plate-like member 17, having if desired, plain edges 18, and having ends undercut as shown at 19 and 20, for cooperation with the portions or flanges shown at 12 and 16.

80 Each element of the type shown in Figure 5 is provided also with a cutaway portion at 21, by means of which engagement may be effected by the use of the finger or of a suitable tool, permitting of convenient removal. Pins 23, constituting marking devices, are so positioned that a distinctive 85 design is formed, which however constitutes a unit of the complete design produced by assembling any desired number of these units of Figure 5.

85 The top 25 carries a handle 26, which may be employed by grasping directly in the hand of the user, or by inserting the hand with the palm downwardly, this upper element carrying marking devices or pins 23', for working out a particular design, it being 90 understood that this may be a fixed arrangement, such for instance as that shown in Figure 6.

95 The bottom element 28 includes flange 29, a similar flange being provided for the top,—and said bottom also carries handles 30, serving an obvious purpose in the use 100 of the article, and in fact of the complete construction, when desired.

105 This bottom element may also carry marking devices 23'', arranged in fixed position, if desired, in order to produce a particular

design,—the upper, lower, and central elements of the complete construction of Figure 1 being used for the various purposes indicated, and being adapted also for assembly, for sale purposes, and for safe keeping when in the hands of the purchaser.

Having described the invention what is claimed is:

1. In a device of the class described, an outer element having an inner flange, radial arms within said element and connected with the walls thereof, segmental plates to be carried by the flange and positioned between the radial arms, and marking devices carried by the plates.
2. In a device of the class described, an outer element, radial arms within said element and connected with the walls thereof, segmental plates to be carried by the radial arms and having chamfered portions engaging the outer element, marking devices carried by the plates, and a cover for the outer element.

3. In a device of the class described, an outer ring element, radial arms within said element, a hub portion with which said arms are connected, segmental plates to be mounted between the radial arms, marking devices carried by the plates, and additional marking means detachably carried by said outer element and constituting a flanged disk member, the flange engaging said ring element.

4. In a device of the class described, an outer element including an inwardly extending flange, radial devices connected with said flange and extending between the latter and the central portion of the outer element, the radial devices being connected at their approaching ends, segmental plates each having an undercut portion adapted to cooperate with the flange, the plates being mounted between the arms, and marking devices carried by said plates.

In testimony whereof I affix my signature.
CARL MARCH.
